UNITED STATES PATENT OFFICE.

JOHN A. DOHERTY, OF NEW YORK, N. Y.

STREET-SWEEPER.

SPECIFICATION forming part of Letters Patent No. 537,278, dated April 9, 1895.

Application filed September 24, 1891. Renewed January 22, 1895. Serial No. 535,822. (No model.)

To all whom it may concern:

Be it known that I, JOHN A. DOHERTY, a citizen of the United States, residing in the city, county, and State of New York, have 5 invented new and useful Improvements in Street-Sweeping Machines, of which the following is a specification.

This invention relates to improvements in street sweeping machines consisting of an 10 adjustable bucket to receive and hold the sweepings delivered thereto by the usual revolving broom, and a suspended box into which the sweepings are to be deposited from time to time from this adjustable bucket, and 15 when a sufficient quantity of sweepings shall have been deposited in said box, the whole may be deposited in separate masses therefrom to be subsequently removed in any convenient manner.

20 Figure 1 represents a side elevation of this machine complete. Fig. 2 is a plan or top view of Fig. 1. Fig. 3 is a central, longitudinal section of Fig. 1, showing the different positions of the bucket to receive and discharge the sweepings delivered thereto by 25 the revolving broom. Fig. 4 is a similar view to Fig. 3, showing the suspended box into which the sweepings are to be deposited from the bucket in position to discharge its contents in a mass in one place; Fig. 5, a transverse, sectional view through the line x, x of 30 Fig. 1, to show more clearly the manner of suspending the bucket, the other parts of the machine, not necessary thereto being omitted.

35 Similar letters of reference indicate corresponding parts throughout the several figures.

The accompanying drawings represent my invention as applied to an ordinary two wheel 40 sweeper, though it is evident that it would be equally well adapted to a three or four wheel sweeper.

A, in the accompanying drawings is the frame of an ordinary sweeping machine with two wheels and designed to be drawn by one 45 animal, upon the axle B, of which is suspended an oscillating, adjustable box C, to receive and contain the sweepings from an adjustable bucket D, from time to time until a sufficient quantity shall have been collected and 50 deposited therein, and subsequently to discharge the mass therefrom in one place by turning the box on its axis to the position

shown in Fig. 4. At the rear end of this sweeper is arranged the usual revolving broom E, adjustable and driven by an endless 55 chain F, from a pulley G, secured to the axle B, and a corresponding pulley H, mounted upon the outer end of the shaft of the broom as shown in elevation Fig. 1, and plan Fig. 2. Directly in front of this revolving broom E, 60 and at the proper distance therefrom is suspended an adjustable bucket D, extending crosswise and somewhat longer than the broom E, in order to receive all the sweepings delivered thereto by the broom. This 65 bucket D, is suspended by chains "a" passing over a roller I, mounted upon the frame A, in suitable bearings, over which roller these chains are to be drawn by a chain b, extending to and connected with a windlass 70 J, to raise and tilt the bucket to deliver its contents into the box C, of the sweeper as shown in dotted lines Fig. 3, and to be again lowered in position to receive the sweepings from the broom in same figure. To limit the 75 up and down movements of this bucket D, slotted guides K, are provided and secured to the frame A, into the slots of which guides the ends of the rod d, extend and to which rod the bucket D is secured. When this bucket D, is 80 lowered and in position to receive the sweepings from the broom, the ends of the rod d, rest in the lower ends of the slots f, and when the bucket is drawn to its extreme upward movement the rod d, will be arrested at the 85 upper ends of the slots and the bucket tilted so as to deliver its contents into the box c, over its rear edge as shown in dotted lines Fig. 3.

As a convenient and practicable means of raising and lowering the bucket D, when required, a windlass J, with hand-wheel d', is provided and placed near the driver's seat, which windlass is connected with the bucket by means of the chains b, a, so that by turning this hand-wheel d', backward and forward 90 the bucket D, may be raised and tilted to discharge the contents therefrom, and lowered to position to receive the sweepings as shown in Fig. 3. It will be observed that when the bucket D, shall have been elevated by means 95 of the hand-wheel d', and chains b, a, to the required height, the guides K, will arrest its further upward movement, and then by continuing to turn the hand-wheel d', the bucket 100

will be tilted backward with its rear edge extending over the edge of the box *c*, to deposit its contents therein as before stated, and represented in dotted lines Fig. 3.

5 The chains *a*, by which the bucket is suspended and by which it is to be raised and lowered are attached thereto in front of the guide-rod *d*, a sufficient distance to tilt the bucket at its extreme upward movement, and
10 to maintain the bucket in a horizontal position while being raised and lowered, the preponderance of weight being in front of the suspension chains.

In order to maintain the front edge of the
15 bucket *D*, in proper position steadily, and independent of the suspension chains *a*, while receiving the sweepings from the broom, stops *h*, are secured to its lower side which bear against the guides *K*, as shown in Figs. 1, 3 and
20 4. By this arrangement of stops, the bucket may be lowered and its front edge maintained in a fixed position to receive the sweepings therein independent of any exact movement
25 of the hand-wheel *d*, of the windlass which would be difficult in the absence of these stops. It will also be observed that this bucket is practically pivoted so as to pass over obstructions and to return by its own gravity in position to receive the sweepings,
30 the guide-rod *d*, being the pivot, and the stops *h*, together with this guide-rod to maintain it horizontally as shown.

As a convenient means for raising and lowering the revolving broom *E*, a lever *L*,
35 mounted upon uprights *M*, secured to the frame *A*, is provided, to the rear end of which are attached the chains *S*, and by which this broom is also suspended in the usual manner, the opposite end of this lever extending for-
40 ward toward the front of the sweeper to be operated by the attendant as shown in Figs. 1, 2, 3, and 4.

In constructing and arranging the box *C*, it should be suspended upon the axle *B*, so
45 that the front side thereof shall be heavier than that in rear of the axle in order to maintain itself in position when empty, and not to turn backward upon the axle of its own weight. To maintain this oscillating box *C*,
50 in position whether loaded or unloaded, a stop-bar *l*, is provided which is supported in bearings *m*, secured to the frame *A*, of the sweeper and against which bar a stop *W*, se-

cured to the box *C*, bears as represented in the several figures. When the load of sweepings in
55 the box is to be deposited in one place, the stop-bar *l*, is withdrawn and the box permitted to turn on its axis to the position shown in Fig. 4, and when empty may again be returned in place and locked to receive the sweepings as
60 before stated. As soon as the sweepings are received from the broom, by the bucket, raised and discharged therefrom into the box in sufficient quantity they are in turn discharged from the box in masses at different places
65 the same as they would be gathered by hand-brooms from windrows left by sweepers not provided with my improvements; and so on the operation may be repeated—the bucket to continue to receive, elevate and discharge
70 its contents into the box and subsequently deposited therefrom at intervals, in different places as before stated.

Having thus fully described my invention, what I claim therein as new, and desire to secure by Letters Patent, is—

1. In a street sweeping machine the combination with an oscillating box to receive and deposit the sweepings therefrom at intervals, of a bucket suspended and capable of being raised and tilted to discharge the sweepings therefrom into said oscillating box, the guides by which the up and down movements of said bucket are governed and limited, the suspension chains by which said bucket is to be raised, and lowered to receive the sweepings being in front of said guides, whereby said bucket is maintained in a horizontal position while being raised and lowered substantially as herein set forth and shown.

2. In a street sweeping machine provided with a bucket suspended and capable of being raised and tilted to discharge the sweepings therefrom, and lowered to a fixed position to receive the sweepings, the guides by which the up and down movements of said bucket are governed and limited, and stops secured to said bucket in front of said guides whereby the bucket is maintained in position while receiving the sweepings independent of the suspension chains substantially as and for the purpose set forth.

JNO. A. DOHERTY.
